Inventor:

A. F. Barry

United States Patent Office.

A. F. BARRY, OF NEW YORK, N. Y., ASSIGNOR TO HIMSELF AND IRA G. LANE, OF SAME PLACE.

Design No. 3,709, dated October 12, 1869.

DESIGN FOR AN ELEVATED OVEN-RANGE.

The Schedule referred to in these Letters Patent and making part of the same.

To all whom it may concern:

Be it known that I, A. F. BARRY, of the city, county, and State of New York, have invented a new and original Design for Elevated Oven-Ranges; and I do hereby declare that the following is a full, clear, and exact description thereof, which will enable others skilled in the art to make and use the same, reference being had to the accompanying drawing, forming part of this specification.

The drawing represents a perspective view of my new design for oven-ranges.

This invention relates to a new design for a range,

constructed in tiers, so that the oven-part is elevated above the main cooking-part.

The invention consists in the general arrangement and ornamentation of the oven-front, which is clearly shown in the drawing, to which reference is made.

Having thus described my invention.

I claim as new, and desire to secure by Letters Patent—

The design for oven-ranges, as shown.
